WATCHCASE

Laurie Jay Campbell, Erie, Pa., assignor to Louis
Marx & Co., Inc., New York, N.Y.

Filed Jan. 3, 1972, Ser. No. 215,238

Term of patent 14 years

Int. Cl. D10—02

U.S. Cl. D42—8 R

FIG. 2

FIG. 1

FIG. 1 is a top plan view of a watchcase showing my new design;

FIG. 2 is a right side elevational view thereof;

FIG. 3 is a bottom side elevational view thereof, the top side being a mirror image thereto;

FIG. 4 is a left side elevational view thereof; and

FIG. 5 is a bottom plan view thereof.

The characteristic feature of my design resides in the projecting ribs of the cylindrical surfaces of a watchcase of the configuration shown, said ribs extending substantially the full length thereof.

I claim:

The ornamental design for a watchcase, as shown and described.
